UNITED STATES PATENT OFFICE.

HERBERT E. VAN DORN, OF CHICAGO, ILLINOIS.

DRAFT-GEAR.

1,380,443.

Specification of Letters Patent.

Patented June 7, 1921.

Application filed September 2, 1919. Serial No. 320,992.

To all whom it may concern:

Be it known that I, HERBERT E. VAN DORN, a citizen of the United States, residing at Chicago, county of Cook, State of Illinois, have invented a certain new and useful Improvement in Draft-Gears, and declare the following to be a full, clear, and exact description of the same, such as will enable others skilled in the art to which it pertains to make and use the same, reference being had to the accompanying drawings, which form a part of this specification.

My invention relates to draft gear devices for railway vehicles of the type in which the entire draft gear mechanism swings through a comparatively wide angle around a vertical pivot at the inner end and it has for its object to produce a simple and novel construction made up of a few strong, durable parts by means of which the drawbar is effectively supported in a swinging housing or casing from which latter it may conveniently be removed and replaced as occasion may require.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a side elevation of a draft gear arranged in accordance with a preferred form of my invention, only a portion of the coupler head being shown;

Fig. 2 is a vertical longitudinal section through the front end of the draft gear shown in Fig. 1, but on an enlarged scale;

Fig. 3 is a horizontal longitudinal section through the parts shown in Fig. 2;

Fig. 4 is a section taken approximately on line 4—4 of Fig. 2, the supporting housing for the drawbar being omitted;

Fig. 5 is a section taken approximately on line 5—5 of Fig. 2;

Fig. 6 is a section taken approximately on line 6—6 of Fig. 2;

Fig. 7 is a section taken approximately on line 7—7 of Fig. 2;

Fig. 8 is a side elevation of a fragment of a modified form of draft rigging, only the supporting housing or casing for the drawbar being shown;

Fig. 9 is a section taken approximately

on line 9—9 of Fig. 8, the drawbar being shown mainly in plan elevation;

Fig. 10 is a section taken approximately on line 10—10 of Fig. 9;

Fig. 11 is a section taken approximately 60 on line 11—11 of Fig. 8;

Fig. 12 is a section taken approximately 65 on line 12—12 of Fig. 8; and

Fig. 13 is a section taken approximately 65 on line 13—13 of Fig. 8.

Referring to Figs. 1 to 7 of the drawings, 1 represents a housing or casing preferably cast integral with the front end of a strong bar, 2, which is adapted to be pivotally connected at its rear end to a suitable fitting 70 on the under side of a railway vehicle, as indicated at 3. The housing or casing is open at the front end and at the bottom. At its rear end the housing is made abruptly narrower as indicated at 4, so as to provide 75 forwardly-facing shoulders, 5. At the bottom of the housing, just in front of the shoulders 5, are inwardly- and forwardly-extending platforms or ledges, 6. Extending rearwardly from the contracted portion of 80 the casing or housing is a cylindrical thimble-like part, 7. Near its front end the housing is again abruptly narrowed, as indicated at 8, so as to provide at opposite sides a pair of rearwardly-facing shoulders, 9, parallel with and directed toward the shoulders 5 at the rear end. The contracted part 8 preferably consists of parallel side plates, 10, connected at the top by a semi-cylindrical roof. The casing or housing is 85 provided with downwardly-extending ears or lugs, 11, on opposite sides thereof just behind the rearwardly-facing shoulders 9. A bolt, 12, is adapted to pass transversely 90 across the bottom of the housing through these ears or lugs. A similar bolt, 13, is adapted to pass transversely through the lower ends of the side plates, 10, of the contracted front end of the housing; the bolt, 13, being in a plane somewhat above the 95 bolt 12.

Within the housing are a pair of cheek plates, 14, lying on opposite sides of the housing and each in engagement with one of the shoulders 9; the cheek plates being supported at their lower ends by the bolt 12 and extending at their upper ends into engagement with the top wall of the housing as best shown in Fig. 6. The cheek plates have a thickness measured trans- 110

versely of the draft gear equal to the width of the shoulders 9 so that the inner faces of the cheek plates in effect form continuations of the inner side walls of the contracted 5 front end, 8, of the housing. Each cheek plate is provided with a rearwardly-projecting horizontal shelf or bracket, 15, having its upper face lying in the same horizontal plane as the upper faces of the platforms 10 or shoulders, 6, at the rear end of the housing. Each cheek plate is also provided at the lower end with a forwardly-projecting plate or flange, 16, through which the bolt 13 may pass, as best shown in Fig. 5; thus 15 positively locking the cheek plates against rocking. The bottom of the housing or casing is closed at the front end by means of a saddle, 17, which is just wide enough to fit between the cheek plates and within the 20 contracted front end of the housing; the bolts, 12 and 13, both passing through the saddle and the saddle thus serving as a spacing device between the cheek plates. The front end, 18, of the saddle is preferably 25 made in the form of a section of a cylinder having the same axis, when the parts are assembled, as the cylindrical upper part of the contracted front end of the casing or housing; so that, when the parts are as- 30 sembed, the saddle and the upper half of the contracted part, 8, of the housing form approximately a cylinder having its axis alined with the axis of the cylindrical thimble 7 at the rear end of the housing.

35 Within the housing is a drawbar comprising a cylindrical front end, 20, a cylindrical rear end, 21, and an intermediate yoke portion, 22; the part 20 being seated in the cylindrical opening formed between the 40 front end of the saddle and the upper portion of the contracted front end of the housing, and the cylindrical part 21 resting in the cylindrical thimble 7. The extreme upper portion of the housing is made nar- 45 rrower than the main portion thereof as indicated at 19; the interior width of the part 19 being only slightly greater than the width of the yoke portion of the drawbar. Extending transversely through the yoke 50 of the drawbar are two follower plates, 23, the rear follower plate bearing against the shoulders, 5, at the rear end of the housing and resting upon the platforms or shelves, 6, while the forward follower plate rests against 55 the rear vertical edges of the cheek plates and upon the brackets or shelves, 15, on the cheek plates. At the points where the drawbar engages with the follower plates it is preferably provided with bosses, 24, which permit the drawbar to turn readily upon its longitudinal axis relatively to the follower plates. Suitable springs, 25 and 26, are arranged between the follower plates, the 60 springs being under an initial compression as is usual.

It will be seen that by removing the bolts 12 and 13, the entire drawbar with the follower plates and springs may conveniently be taken out through the bottom of the housing, the saddle and the cheek plates of course being taken out at the same time. In the same way, when the drawbar is to be placed in position, it is slipped upwardly and rearwardly through the bottom of the housing and the cheek plates and saddle are then placed in position and the whole locked together by the insertion of the bolts 12 and 13. When the drawbar is in place it is supported in cylindrical bearings at the front and rear ends so that it may turn about its longitudinal axis; but at the same time the turning movement of the drawbar is limited by reason of the fact that the yoke will engage with a solid portion of the housing whenever the drawbar has been turned through a small angle in either direction and will thus prevent further turning movement in that direction.

On the front end of the drawbar is a downwardly-projecting arm, 27, carrying a rearwardly-projecting thimble, 28, open at the front end. In the thimble is a spring, 29, acting on a plunger, 30, which projects beyond the front end of the thimble. An L-shaped bracket, 31, is hung at the free end 90 of one of its arms upon a horizontal pin, 32, passing through the front end of the drawbar; the lower end of the latter arm bearing against the plunger 30, and the other arm of the bracket extending forwardly so as to 95 underlie and serve as a rest for a coupler head, 33, hung at its rear end on the pin 32. It will be seen that the coupler head may be swung upward freely from a position in which it is yieldably supported by the 100 bracket and, also, that it may swing downwardly below its normal position if sufficient force is applied to compress the spring 105 acting on the bracket.

In Figs. 8 to 13 I have illustrated a slight 110 modification of my improved draft rigging adapting it for use in connection with a drawbar terminating at its rear end in a stem instead of a yoke. Referring to these figures, 40 represents a casing or housing 115 similar to the member 1 in the other arrangement in that it is carried on the front end of a heavy bar or stem, 2, and is open on the front and bottom sides. The rear end of the casing or housing is in the form 120 of a cylindrical thimble, 41, smaller in diameter than the width of the casing or housing, so as to provide forwardly-facing shoulders, 42, against which a rear follower plate, 43, may bear. The front end of the 125 casing or housing is contracted in width, as indicated at 44, so as to provide vertical rearwardly-facing shoulders, 45, parallel with and directed toward the shoulders 42 at the rear. The upper half of the housing 130

may be made semi-cylindrical. In the front end of the housing are cheek plates, 46, filling in the space at each side behind the shoulders 45 and adapted to constitute abutments against which a front follower plate, 47, may bear. The cheek plates are supported by a transverse bolt, 48, corresponding to the bolt 12 in the other form of rigging; the bolt 48 passing through ears, 49, arranged at the lower edges of the sides of the housing. A saddle, 50, corresponding to the saddle, 17, in the other form of rigging, closes the bottom of the casing or housing at the front end of the latter; the saddle being supported at its rear end by the bolt, 48, and at its front end by a transverse bolt, 51, passing through ears, 52, arranged at the sides of the housing in front of the ears 49. The rear end of the saddle serves as a spacer between the cheek plates. The top of the saddle is made concave, being in the form of a section of a cylinder so that when the parts are assembled the housing has in the front end a substantially cylindrical opening whose axis registers with the axis of the cylindrical thimble, 41, at the rear end. The drawbar, 53, has a cylindrical front end, 54, which rests in the cylindrical opening in the front end of the casing or housing. The drawbar is provided with a rearwardly-extending axial stem, 55, which passes through a coiled spring, 56, lying between the two follower plates and has on the rear end thereof, beyond the rear follower plate, a cylindrical nut, 57, which fits rotatably into the cylindrical thimble 41. As best seen in Fig. 11, the front end of the housing or casing has in the top thereof a longitudinal groove, 58, opening upwardly out of the cylindrical bearing seat, and the drawbar has a longitudinally-extending rearward projection, 59, lying within this groove when the parts are assembled, but narrower in width than the groove so as to permit the drawbar to turn through a limited angle around its longitudinal axis.

It will therefore be seen that in this form of my invention, as in the other, the drawbar is supported in cylindrical bearings at the front and rear end so that it may turn freely about its longitudinal axis, while means are provided for limiting the turning movement in either direction from a normal position. Therefore in each form of my invention I overcome an important objection to the so-called rigid type of drawbar by permitting an appreciable turning movement about the longitudinal axis sufficient to relieve the draft rigging from injurious twisting stresses during relative lateral rocking or swaying of cars coupled together.

While I have illustrated and described with particularity only a single embodiment of my invention, in two slightly modified forms, I do not desire to be limited to the

exact structural details thus illustrated and described; but intend to cover all forms and arrangements which come within the terms employed in the definitions of my invention constituting the appended claims.

70

I claim:

1. In a draft rigging, an integral housing open at the front end and at the bottom, said housing having a cylindrical seat at the rear end, a removable saddle forming a closure 75 for the bottom of the housing at the front end, said saddle and the overlying portion of the housing forming a cylindrical bearing seat co-axial with said cylindrical seat at the rear end of the housing, a drawbar 80 extending into said housing and having cylindrical portions fitting said seats, and spring mechanism arranged within the housing and serving yieldingly to hold the drawbar against longitudinal movements. 85

2. In a draft rigging, a bar having a housing formed integral with the front end thereof, said housing being open at the front and at the bottom, said housing having a cylindrical bearing seat at the rear end behind the opening in the bottom, a detachable saddle extending across the bottom of the housing near the front end, said saddle and the overlying portion of the housing forming a cylindrical bearing seat co-axial with the 95 aforesaid seat, a drawbar and spring mechanism adapted to be inserted through the open bottom of said housing, said drawbar having cylindrical portions adapted to fit into said seats when the parts, including the 100 saddle, are assembled.

3. In a draft rigging, a housing open at the front and at the bottom, said housing having at the rear end a rearwardly-projecting cylindrical thimble, a removable saddle 105 forming a closure for the bottom of the front end of the housing, said saddle and the overlying portion of the housing forming a cylindrical bearing seat co-axial with the aforesaid thimble, and a drawbar and 110 spring mechanism adapted to be entered into the housing through the open bottom when the saddle is removed, said drawbar having cylindrical portions at the rear end and at the front end adapted to be seated respectively in said thimble and in said cylindrical seat. 115

4. In a draft rigging, a housing open at the front end and at the bottom, said housing having a rearwardly-projecting cylindrical thimble at the rear end and with shoulders in advance of said thimble for engaging with a rear follower plate, said housing having in the front end rearwardly-facing shoulders, a detachable cheek plate 125 lying behind each of the latter shoulders and in engagement therewith, said cheek plates being removable through the open bottom of the housing, a front follower plate engaging with the rear edges of said 130

- cheek plates, a drawbar extending into said housing and having a portion seated in said cylindrical thimble, a spring between said follower plates, and a removable saddle extending across the under side of the housing near the front end of the latter to support the front end of the drawbar.
5. In a draft rigging, a housing open at the front end and at the bottom, said housing having a cylindrical thimble extending rearwardly from the rear end thereof and having forwardly-directed shoulders on opposite sides of and in the vicinity of the thimble, short horizontal ledges integral 15 with said housing in advance of the aforesaid shoulders, rearwardly-directed shoulders within the housing on opposite sides thereof near the front end, detachable cheek plates adapted to be inserted through the 20 open bottom of the housing lying behind and in contact with said rearwardly-directed shoulders, and a detachable saddle extending across the bottom of the front end of the housing to close the same, said saddle and 25 the overlying portion of the housing being shaped to form a cylindrical bearing seat co-axial with said cylindrical thimble at the rear end of the housing.
6. In combination, a drawbar, a horizontal spring-pressed plunger lying below and extending parallel with the drawbar, a bracket hinged at its upper end to the front end of the drawbar and extending downwardly in front of said plunger, said bracket 30 having a forwardly-extending arm, and a coupler head hinged to said drawbar so as to swing about the hinge axis of said bracket and resting upon said arm.
7. In combination, a drawbar, a horizontal hinge pin supported at the front end 40 of said drawbar, a horizontal spring pressed plunger lying below and extending parallel with the drawbar, a bracket mounted on said hinge pin and extending downwardly in front of said plunger, said bracket having 45 a forwardly extending arm, and a coupler head hung on said hinge pin and resting loosely upon said arm.
8. In combination, a drawbar, a horizontal spring pressed plunger lying below and 50 extending parallel with the drawbar, a bracket hinged at its upper end to the front end of the drawbar at a considerable distance above said plunger and extending downwardly in front of said plunger, said 55 bracket having a forwardly extending arm, and a coupler head hinged to said drawbar and resting upon said arm.
9. In a draft rigging, a housing open at the front end, said housing having a substantially cylindrical seat at the rear end and a substantially cylindrical seat at the 60 front end, the lower portion of the cylindrical seat at the front end being contained in a detachable saddle, a drawbar extending 65 into said housing and having separated cylindrical portions fitting said seats, and spring mechanism associated with the drawbar and lying in the housing between the front end of the rearmost cylindrical seat 70 and the rear end of the front cylindrical seat.

In testimony whereof, I sign this specification.

HERBERT E. VAN DORN.
